CLAIM

The ornamental design for a handset, as shown and described.

DESCRIPTION

FIG. 1 is a front elevational view of the handset, shown in an open position;

FIG. 2 is a rear elevational view thereof;

FIG. 3 is a left side elevational view thereof;

FIG. 4 is a top plan view thereof;

FIG. 5 is a right side elevational view thereof;

FIG. 6 is a bottom view thereof;

FIG. 7 is a front elevational view of the handset, shown in a closed position;

FIG. 8 is a rear elevational view thereof;

FIG. 9 is a left side elevational view thereof;

FIG. 10 is a top plan view thereof;

FIG. 11 is a right side elevational view thereof; and,

FIG. 12 is a bottom view thereof.

The broken lines shown throughout the views, which are immediately adjacent to the shaded areas and define unshaded regions, represent the bounds of the claimed design, while all other broken lines are directed to environment and are for illustrative purposes only; the broken lines form no part of the claimed design.
